UNITED STATES PATENT OFFICE.

GEORGE S. GATCHELL, OF ROSELLE PARK, NEW JERSEY, ASSIGNOR TO THE SINGER
MANUFACTURING COMPANY, A CORPORATION OF NEW JERSEY.

STRIP-GUIDE FOR SEWING-MACHINES.

1,347,503.

Specification of Letters Patent.

Patented July 27, 1920.

Application filed April 6, 1917. Serial No. 160,087.

To all whom it may concern:

Be it known that I, GEORGE S. GATCHELL, a citizen of the United States, residing at Roselle Park, in the county of Union and 5 State of New Jersey, have invented certain new and useful Improvements in Strip-Guides for Sewing-Machines, of which the following is a specification, reference being had therein to the accompanying drawings.

10 This invention relates to sewing machines particularly of the cylinder-bed type and has for an object to provide a machine of the class described with guiding means adapted to apply a stay-strip to the under 15 side of the work.

The particular purpose for which this machine is adapted is to flatten out an initially stitched seam formed in leather goods, such as shoe-uppers; and to apply a stay-strip of 20 canvas material to the underside of the seam to cover the rib formed by the projecting edge-portions of material. The machine is, however, capable of being used for various 25 other purposes wherein a narrow strip of material is to be stitched or applied to the under surface of a body-fabric.

In its preferred embodiment the invention comprises a cylinder-bed sewing machine formed with the usual hollow work-supporting arm whose free end is preferably 30 fitted with a removable cylindrical end-cap having a circular end-wall whose exposed face is channelled diametrically to form an upwardly extending strip-guiding passage-way adapted to receive a stay-strip leading 35 upwardly from a source of supply disposed below the machine and to deliver said stay-strip to the stitching plane. The end-wall of the cylindrical cap-member carries adjustable guides which serve to confine the 40 stay-strip within the strip-guiding channel. In the present instance the work-arm carries a throat-plate whose forward end-portion is extended in front of the end-wall of said 45 cap-member and is provided with a tape-guiding slot which is disposed substantially in register with the strip-guiding channel above referred to. The throat-plate carries a pair of adjustable guides which serve to 50 control the position of the stay-strip relatively to the line of seam-formation and to adapt the machine to handle various widths of tape.

In the accompanying drawings, Figure 1 55 is a view of the essential features of a cylin-

der-bed sewing machine embodying the present invention. Fig. 2 is a side-elevation of the same, and Fig. 3 is a horizontal cross-section through the end-cap of the machine.

In the accompanying drawings, the invention is illustrated as embodied in a cylinder-bed machine having the usual cylindrical work-supporting arm 1 within which is housed the usual feeding mechanism including the feed-dog 2 with which co-operates the presser-foot 3 formed with the guiding rib 4 and apertured at 5 to receive the spaced reciprocating needles 6 carried by the reciprocating needle-bar 7 which is journaled within the head 8 and actuated by 60 any suitable mechanism.

The cylindrical wall of the hollow work-arm is formed at one side with a longitudinally extending dove-tailed groove 9^a within which is slidably fitted the rearwardly 65 projecting shank 9^b of the hollow cylindrical end-cap 9 which forms a housing for the usual loop-taker (not shown) and is closed at its free end by means of the substantially circular end-wall 10. To guide a stay-strip 70 from a source of supply below the work-arm to the stitching plane, the end-wall 10 is, in the present instance, channelled vertically and diametrically at 11. The width of this 75 channel is sufficient to accommodate a tape of 80 the desired maximum width. To retain the tape in the channel 11, the end-wall 10 may be channelled horizontally at 12, 12 to receive guide-blocks 13, 13 each of which is cut away at its inner end to form a guiding 85 shoulder 15 and a tape-confining lip 16. The guides 13 are slotted at 17 and secured in adjusted position in their respective guideways 12 by means of the screws 18, 18.

The work-arm 1 supports a throat-plate 95 19 which is preferably formed with a flat raised portion 20 defining the stitching plane and apertured as usual to receive the feed-dog 2. The throat-plate 19 is secured to the arm 1 at its rearward end by means of 100 the usual screws, one of which is shown at 21, and is preferably elongated so as to project forwardly in advance of the end-wall 10. Registering with the guideway 11 is the rectangular tape-guiding aperture 22 formed 105 in the throat-plate 19, as shown in Fig. 2. The throat-plate may carry adjustable means for guiding the tape and defining the lateral position thereof relatively to the stitching point. In the present instance, 110

said adjustable means may comprise a pair of bent wires 23 having tape-supporting end-portions 24 and tape-guiding side-portions 25. The guiding devices 23 are adapted for lateral adjustment to properly control various widths of stay-strip material and, in the present instance, are secured in adjusted position within the transverse grooves 26 by means of a screw 27 whose head is larger in diameter than the distance between said grooves.

From the above description it will be obvious that strip material of various widths may be properly aligned with and guided to the stitch-forming mechanism of a cylinder bed machine and applied to the under side of the main-body of material being stitched. The strip material may be supplied from a suitable reel disposed below the machine and entirely out of the way. Being fed upwardly from below the tape does not obstruct the operator's view of the work nor does it interfere in any way with the necessary operations involved in the handling of the work while presenting it to the stitch-forming mechanism for application of the stay-strip.

It is often desirable to remove the end-cap of the machine and gain access to the loop-taker housed therein without severing the tape or disturbing its position above the throat-plate. To facilitate this operation it will be noted that the free ends of the tape confining lips 16 are spaced apart to permit the ready removal of the tape from the guiding passageway 11 by passing it through the space between said lips prior to the removal of the end-cap effected by sliding it axially off the free end of the work-arm. The end wall 10 may be cut away at 10° or otherwise spaced from the under face of the throat-plate to provide clearance for the tape during the removal or replacement of the end-cap, as will be readily understood.

The specific construction shown and described is obviously susceptible of material modification both in the form and arrangement of the various parts without departure from the invention.

Having thus set forth the nature of the invention, what I claim herein is:—

1. In a cylinder-bed sewing machine, the combination with a work-supporting arm, stitch-forming mechanism including a pair of needles, and work-feeding mechanism, of means for guiding a previously stitched seam between said needles, means for guiding a stay-strip upwardly across the free end of said work-arm; and adjustable means adjacent the stitching plane for guiding said stay-strip to the stitch-forming mechanism.

2. In a cylinder-bed sewing machine, the combination with a work-supporting arm,

stitch-forming mechanism, work-feeding mechanism and a presser-foot, of means sustained below the stitching plane and in advance of the presser-foot for guiding a stay-strip upwardly across and within the periphery of the free end of the work-arm and delivering it to said stitch-forming and feeding mechanism in advance of said presser-foot.

3. A sewing machine comprising, in combination, a frame including a hollow work-supporting arm whose free end-portion is formed with an upwardly extending strip-guiding passageway, means for varying the effective width of said passageway, and stitch-forming and work-feeding mechanisms incorporated in said frame.

4. A sewing machine comprising, in combination, a frame having a hollow work-supporting arm including an end-wall, said end-wall being cut away to form an upwardly extending strip-guiding channel, stitch-forming and work-feeding mechanisms incorporated in said frame, guide means between said channel and stitch-forming mechanism, and means for retaining the strip in said channel.

5. A sewing machine comprising, in combination, a frame having a hollow work-supporting arm including an end-wall, stay-strip guiding means sustained by said end-wall, a throat-plate sustained by said arm and projecting forwardly of said end-wall and formed with a strip-guiding aperture, and stitch-forming and work-feeding mechanisms incorporated in said frame.

6. A sewing machine comprising in combination, a frame having a hollow work-supporting arm including an end-wall, stay-strip guiding means sustained by said end-wall, a throat-plate sustained by said arm and projecting forwardly of said end-wall and formed with a strip guiding aperture, and adjustable guiding means carried by said throat-plate for controlling the position of the strip relatively to the line of seam-formation.

7. A sewing machine having, in combination, a frame comprising a hollow work-supporting arm including an end-cap, said end-cap being formed with an upwardly extending strip-guiding channel, adjustable strip-guides carried by said end-cap and adapted to confine the stay-strip within said channel, and stitch-forming and feeding mechanisms incorporated in said frame.

8. A sewing machine having, in combination, a frame comprising a hollow work-arm, a removable end-cap sustained at the free end of said work-arm and formed with an upwardly extending strip-guiding passageway, and means for confining the strip within said passageway, said means comprising spaced elements whereby the strip may be readily removed from said guide-

way by lateral displacement through said space.

9. A sewing machine having, in combination, a frame comprising a hollow work-arm, a throat-plate supported thereon and having a vertical strip-guiding aperture, a removable end cap on said work-arm, said cap having a portion cut away below and in rear of said aperture to provide clearance for 10 said strip when the cap is removed.

10. A sewing machine comprising, in combination, a hollow work-supporting arm including an end wall, a throat-plate on said arm and overhanging said end wall, a strip-guiding aperture in the overhanging portion, and adjustable strip-guiding means 15 above said aperture.

11. A sewing machine comprising, in combination, a hollow work-supporting arm including an end wall, stay-strip guiding means on said end wall, a throat-plate on said arm and overhanging said end wall, a strip-guiding aperture in the overhanging portion of the throat-plate, and guiding 25 means above said aperture.

12. In a sewing machine, the combination of a hollow cylindrical work-supporting arm, stitch-forming mechanism, a presser-foot, means for guiding a stay-strip across 30 the end of said arm, and means extending from the arm in advance of the presser-foot for guiding the strip into stitching relation to a seam to be covered.

13. In a sewing machine, the combination of a hollow cylindrical work-supporting arm, stitch-forming mechanism, a presser-foot, and means for guiding a stay-strip into stitching relation to a seam to be covered, said means comprising a guide on the end of the work-supporting arm and a second guide 40 disposed on top of the arm between said first guide and the presser-foot. 35

14. In a sewing machine, the combination of a work-supporting arm, stitch-forming mechanism, and means for guiding a stay- 45 strip into stitching relation to a seam to be covered, said means comprising a passage way extending across the end of said arm and a pair of adjustable guides adjacent the discharge end of said passage way. 50

15. In a sewing machine, the combination of a work-supporting arm, stitch-forming mechanism, means for guiding a stay-strip across the end of said arm, and adjustable means for centering the strip with relation 55 to the stitch-forming mechanism.

16. In a sewing machine, the combination of a work-supporting arm, stitch-forming mechanism, means in advance of the latter for spreading a seam to be covered, and adjustable means for centering and guiding a stay-strip into stitching relation to the seam. 60

In testimony whereof, I have signed my name to this specification.

GEORGE S. GATCHELL.
